UNITED STATES PATENT OFFICE.

HARRY W. LANSING, OF LOS ANGELES, CALIFORNIA.

DESIGN FOR A SOUVENIR-PENNY OF CALIFORNIA.

47,537.

Specification for Design.

Patented July 6, 1915.

Application filed March 3, 1915. Serial No. 11,870. Term of patent 3½ years.

To all whom it may concern:

Be it known that I, HARRY W. LANSING, a citizen of the United States, residing at Los Angeles, in the county of Los Angeles, State of California, have invented a new, original, and ornamental Design for a Souvenir-Penny of California, of which the following is a specification, reference being had to the accompanying drawing, forming part thereof.

In the drawings: Figure 1 is a plan view of a souvenir penny of California, showing my new design, and Fig. 2 is a plan view of the back side of same.

I claim:

The ornamental design for a souvenir penny of California, as shown.

HARRY W. LANSING.

Witnesses:

ELWOOD H. BARKELEW,
JAMES T. BARKELEW.
